2 SHEETS—SHEET 2.

UNITED STATES PATENT OFFICE.

JOHN P. GARDNER, OF SAN FRANCISCO, CALIFORNIA.

METALLIC RAILROAD-TIE AND FASTENER.

1,311,386.

Specification of Letters Patent. Patented July 29, 1919.

Application filed November 30, 1917. Serial No. 204,700.

To all whom it may concern:

Be it known that I, JOHN P. GARDNER, a citizen of the United States, residing at San Francisco, in the county of San Francisco, and State of California, have invented certain new and useful Improvements in Metallic Railroad-Ties and Fasteners; and I do hereby declare the following to be a full, clear, and exact description of the invention, such as will enable others skilled in the art to which it appertains to make and use the same.

This invention relates to metallic railroad ties and fasteners and the primary object of the invention is to provide an improved fastener for holding the rails in engagement with the metallic railroad ties and to prevent any movement of the rails in relation to the ties and thus eliminate the creeping and spreading of the rails.

Another object of the invention is to provide an improved fastener for metallic railroad ties embodying a pair of sliding keys which are mounted in guideways formed on the upper surface of the metallic tie, the keys being adapted to engage the rails and absolutely prevent the same from moving in relation to the ties.

A still further object of the invention is to provide an improved plate positioned between the rails and ties to absorb shocks therebetween and an improved means for holding the plate in position on the tie.

A still further object of the invention is to provide an improved device of the above character, which is durable and efficient in use, one that is simple and easy to manufacture, and one that can be placed upon the market at a reasonable price.

With these and other objects in view, the invention consists in the novel construction, arrangement and formation of parts, as will be hereinafter more specifically described, claimed and illustrated in the accompanying drawings, forming a part thereof in which:

Figure 1 is a side elevation of the improved railroad tie and fastener and showing the rails positioned on the tie.

Fig. 2 is a plan view of the improved tie showing the rails in locked position thereon.

Fig. 3 is a detail longitudinal section taken on the line 3—3 of Fig. 2.

Fig. 4 is a transverse section taken on the line 4—4 of Fig. 1.

Fig. 5 is a detail perspective view of one

end of the tie showing the guide way for the locking bolts.

Fig. 6 is a detail perspective view of the shock absorber plates.

Fig. 7 is a detail perspective view of one of the locking bolts and showing the bottom of the same.

Fig. 8 is a detail plan view of the rails showing the notches in the base thereof for receiving the locking bolts.

Referring to the drawings in detail, wherein similar reference numerals designate corresponding parts throughout the several views, the numeral 1 generally indicates the improved railroad tie, which is of I-beam formation and includes the base 2, the upstanding flange 3, and the upper flange or head 4 which is preferably cut away intermediate its ends as at 5 so as not to interfere with the tamping of the ties. 75

The head 4 of the tie 1 is preferably cut to provide a plurality of tongues 6 which are bent upwardly to define a guide way 7 the purpose of which will hereinafter more fully appear. The tongues 6 are formed ad-

jacent each end of the tie and on each side of the rail support 8. The rail support 8 is formed by leaving the upper flange or head 4 of the I-beam in its original form. Bolts 9 are slidably mounted in the guide ways 7 80

on each side of the rails which are indicated by the numeral 10. Certain of the tongues 6 have their upper ends bent angularly and inwardly toward each other as at 11 and prevent upward movement of the bolt in the

guide way and facilitate the positions of the bolts in the guide ways. Positioned intermediate the tongues which have their upper ends bent inwardly as at 11 are locking tongues 12 which continue above the other 90

tongues and are suitably apertured for the reception of a sliding cotter pin or other fastening element 14. Each of the bolts has a transverse semi-circular groove 15 formed in its upper surface, which the cotter pin 100

slides in and absolutely prevents movement of the bolt in relation to the ties. The bolts 9 are formed substantially rectangular and have their inner ends beveled as at 16 which

are adapted to engage the flange or base 17 105 of the rails 10 and prevent upward movement of the same. The lower side edges of

the bolts 9 are beveled inwardly toward each other as at 18 to provide a pointed tongue 19 which is adapted to engage in V-shaped 110

notches 20 formed in the side edges of the base 17 of the rails 10 and thereby prevent relative movement of the rails transversely in relation to the ties. The notches 20 can 5 be made in the rails with a chisel or any other suitable instrument. Positioned on the rail supporting flange 8 are shock absorbent pads 21 which are preferably formed of pressed paper or other suitable material 10 and the same forms a resilient seat for the rails 10 and thus forms a shock absorbing cushion. The side edges of the resilient plate 21 are provided with inwardly projecting lugs 22 which extend toward the 15 tongues 6, the innermost pairs of which are flattened and bent inwardly toward each other as at 23, which prevents upward movement of the plates in relation to the tie. The lugs 22 are provided with cut out portions 20 24 which taper inwardly as at 25 to receive the V-shaped tongue 19 on the locking bolt 9 and allow the inward movement of the same.

The grooves 15 which are formed in the 25 upper surface of the locking bolts 9, are so arranged that the same only aline with the openings 13 formed in the tongues when they are in locked position.

From the foregoing description it will be 30 seen that an improved metallic tie is provided which includes an improved type of rail fastener which will absolutely prevent inward and outward movement of the rails in relation to the ties. With ties of this 35 character only three ties are necessary for each rail length, thereby resulting in a great saving of the ties in which a greater number are required for each rail length.

In practice, I have found that the form of 40 my invention, illustrated in the accompanying drawings and referred to in the above description, as the preferred embodiments, is the most efficient and practical; yet realiz-

ing the conditions concurrent with the adoption of my device will necessarily vary, I desire to emphasize the fact that various minor changes in details of construction, proportion and arrangement of parts may be resorted to, when required, without sacrificing any of the advantages of my invention as 45 50 set forth.

What I claim as new is:—

1. A rail tie and fastener comprising a base adapted to support a rail, guide tongues formed on each side of the base and extending longitudinally of the same and arranged on each side of the rail, locking bolts slidably mounted between the tongues, certain of said tongues having the upper ends thereof bent inwardly toward each other to 55 60 form retaining members, certain other of said tongues having alined apertures formed therein, and transversely extending locking members slidably mounted in the apertures for engaging said locking bolts to hold the 65 same in engagement with the rail.

2. In combination, a rail having V-shaped notches formed in the side edges of the base thereof, of a rail tie and fastener including a base arranged to receive the rail, guideways 70 formed on the base, locking bolts slidably mounted in the guideways, means engaging said bolts to prevent the removal thereof, shock absorbing pads arranged on the base having V-shaped notches formed in the sides 75 thereof, the inner ends of said bolts having V-shaped tongues adapted to engage said notches formed in the rail and pads, as and for the purpose specified.

In testimony whereof I affix my signature 80 in presence of two witnesses.

JOHN P. GARDNER.
